Specification of Letters Patent.

Patented Oct. 12, 1915.

No Drawing.

Application filed April 22, 1914. Serial No. 833,808.

To all whom it may concern:

Be it known that I, GEORGE HOPP, a citizen of the United States of America, residing at New York, in the county of Bronx and State of New York, have invented certain new and useful Improvements in Safety-Treads and Methods of Producing the Same, of which the following is a specification.

- 10 The present invention relates to safety treads and has for its object to provide a safety tread which will be harder, tougher and more durable than the hitherto used treads.
- 15 To accomplish my object I mix under suitable pressure and temperature some abrasive material such as carborundum with phenolic condensation bodies, such as condensation products of phenolic bodies with
- 20 formaldehyde or with anhydrous hexamethylene tetramin, which mixture is applied as a layer on a suitable base which may be of metal, any textile material, rubber or rubber composition, and treated under suitable conditions of temperature and pressure.
- 25

What I claim and desire to secure by Letters Patent is:

1. A safety tread consisting of a base and a layer composed of abrasive material and a phenolic condensation body.
2. A safety tread consisting of a metal base and a layer of abrasive material and phenolic condensation body.
3. A method of producing a safety tread 35 consisting in mixing an abrasive material with phenolic condensation bodies, applying a layer thereof to a base, and treating the whole under suitable conditions of temperature and pressure.
4. A method of producing a safety tread 40 consisting in mixing abrasive material with phenolic condensation products, applying a layer thereof to a metal base, and treating the whole under suitable conditions of temperature and pressure.

In testimony whereof I affix my signature in presence of two witnesses.
